ALIGNING DEVICE

George Rogers Brodie, Lower Merion Township, Montgomery County, Pa., assignor to Fred'k H. Levey Company, Inc., New York, N. Y., a corporation of New York

Application December 10, 1954, Serial No. 474,474

11 Claims. (Cl. 271—87)

This invention relates to the art of printing and more particularly to the stacking and accurately aligning the corresponding edges of printed sheets of paper, or the like. It provides a novel machine of particular utility in the aligning and stacking of folded sheets, especially folded signatures as they are rapidly delivered from the folder of a rotary, web-type printing press:

As is well known in the printing art, and particularly in magazine and book printing, it is customary to equip such presses with mechanisms adapted to receive the printed web and to cut and fold the web to form what are known as signatures. These signatures usually consist of one or more printed sheets of equal size uniformly folded together. The length and breadth of signatures may vary over a considerable range, depending on the particular press set-up. Frequently, signatures will measure about 15 $\frac{1}{4}$ inches by 5 $\frac{3}{4}$ inches; the fold usually being along one of the long edges of the signature, and the invention will be more specifically described and illustrated with respect to signatures of those general proportions.

The signatures are rapidly delivered by the folding mechanism and must be collected and stacked for subsequent assembling with other signatures to form a complete publication. The aligning and stacking of the signatures as they come from the folder is usually done by hand and care must be exercised to avoid damaging their edges. The aligning is usually accomplished, to a more or less imperfect extent, by taking a pile of the signatures and tapping the edges of the pile on a flat surface. But even though a relatively thin pile of the signatures is so tapped, there is considerable resistance to their alignment due to friction between adjacent sheets. Therefore, any projecting edges of the signatures are frequently damaged in this aligning operation. Also, the procedure is usually tedious, time-consuming and relatively costly.

The present invention provides a machine for automatically aligning signatures and the like, whereby they are accurately aligned without injury to their edges and manual operations are minimized.

In accordance with my present invention, the signatures are delivered in rapid succession from the folder to the upper portion of a chute conforming generally in cross-section to the length and breadth of the signature. The signatures enter the chute separately along a substantially horizontal plane so that each signature is permitted to fall vertically in the chute for a substantial distance without frictional contact with the preceding or following signature, thus permitting each signature to be freely moved endwise, or cross-wise, within the chute to bring their edges into alignment with the stack of signatures which have accumulated within the chute. The lower portion of the chute is curved at an angle of about 90° so that the aligned signatures leaving the chute exit are in a substantially vertical plane.

The aligning of the signatures within the chute is further promoted by means for vibrating the chute and the aligning may be further facilitated by guides and

2

other auxiliary equipment hereinafter more fully described and illustrated.

A particularly advantageous embodiment of the invention is represented by the accompanying drawings, of which

Figure 1 is a side view of the machine, in perspective showing signatures in aligned position;

Fig. 2 is a front end view of the machine, also in perspective;

Fig. 3 is a somewhat enlarged perspective view of the chute and a cooperating receiving table; also showing a stack of aligned signatures;

Fig. 4 is a still further enlarged perspective view of the chute showing auxiliary equipment in greater detail, and

Fig. 5 is a detailed side view in perspective of the chute with auxiliary equipment and driving mechanism for operating the same.

Referring more particularly to Figs. 1 and 2 of the drawings, the stacking and aligning mechanisms are supported by a rigid rectangular bed frame composed of side members 1 and end members 2 fastened together at the corners as by welding. The bed frame is, in turn, supported by leg 3 extending through adjustable sleeves 4, secured, as by welding, to the blocks 5 which, in turn, are welded to the side members of the bed frame. The heights of the bed frame may be adjusted and the frame leveled by sliding the legs through the respective sleeves 4 and, when proper adjustment has been made, the position of the legs within the sleeves is maintained by means of set screws 6.

The chute for receiving and aligning the signatures is positioned at the rear end of the bed frame and is formed by substantially parallel end walls 7 and 8 and substantially parallel front and rear side walls 9 and 10, respectively, forming a rectangular upper portion of the chute conforming generally to the length and width of the particular signatures to be stacked. The walls of the chute are, with advantage, fabricated of Plexiglas, or like rigid transparent material, so that the course of the signatures through the chute can be readily observed.

The end walls 7 and 8 are positioned at a slight angle from the vertical, for reasons which will hereinafter appear. The rear wall 10 is so curved and extended as to form the bottom exit of the chute at an angle substantially 90° from the inlet end. The front wall 9 may, if desired, be extended downwardly along an arc parallel to rear wall 10 or the lower end of wall 9 may be omitted, as shown in the drawing.

The end walls 7 and 8 are rigidly fastened to the side walls 9 and 10, as by means of brackets 11. The end walls are, in turn, supported by brackets 12 having flanges 13 at their lower ends by which the brackets are secured to rubber cushion blocks 14 which are, in turn, fastened to the bed frame. The cushion blocks are provided to permit vibration of the chute.

Extending outwardly from the chute exit along the plane of the lower wall of the exit is a receiving table, more clearly shown in Figure 2 of the drawings, composed of parallel cross members 15 and spaced, longitudinal plates 16 secured to the cross members as by machine screws 17. Extending along one side of the receiving table is a side guide composed of a rigid plate 18 secured, as by means of screws, to upward extensions 19 of the cross members 15.

The receiving table and side guide are supported by the bed frame and are rigidly fastened thereto by means of blocks 20 secured, as by welding, to the bed frame and rods 21 extending through blocks 20 and the respective ends of the cross members 15.

At each end of the table, there are provided three sprockets or pulleys 22, rotatably mounted on shafts 23. Extending about each set of pulleys is a conveyor belt 24

which together form a conveyor surface substantially flush with the chute exit and adapted to move along the table from the chute exit as the stacked signatures are delivered from the chute with the signatures lying in a substantially vertical plane.

At each end of the receiving table side guide, there is a sprocket or pulley 25 rotatably mounted on shafts 26 and supported by bearing blocks 27. Extending about the pulleys 25 is an endless belt 28 adapted to move along the surface of guide plate 18 in a direction away from the chute.

In order to avoid slippage of the belts 24 and 28, I have, with advantage, used belts such as conventionally used as timing belt drives and for the pulleys I have used sprockets having gear-like teeth adapted to cooperate with the inward projections on the belt, as shown in the drawings. At least one of each set of sprockets is driven, advantageously by variable speed means, so as to move the delivered stacked signatures uniformly along the table at the desired rate.

While moving along the receiving table, the stacked signatures are held in a vertical position by means of a relatively heavy angle iron 29 which rests freely on the conveyor belts and is moved thereby along the table with the stacked signatures as they accumulate.

The outer end of the receiving table is provided with a cradle composed of parallel angle irons 30 secured by welding or other suitable means to plate 31, which is hinged at 32 to the outer end of the table. As shown more clearly in Figure 2 of the drawings, the angle irons 30 are composed of parallel arms 33 extending longitudinally of the table between the space plates 16 so that their upper surfaces are lower than the surface of the conveyor belts 24. Arms 34 of these angle irons extend substantially perpendicular to the arms 33. This cradle serves to swing a stack of signatures from the horizontal to the vertical position, as more clearly shown in Figure 1, to facilitate subsequent handling and transportation to a place of storage.

In operation, the signatures are delivered to the chute, as by means of a horizontal conveyor belt such as shown at 35. This belt is usually operated at a relatively high speed so that the signatures are shot from the belt against the end wall 7 of the chute. The signatures thus enter the chute separately along a generally horizontal plane and fall freely by gravity onto the pile of signatures which has accumulated in the chute. The upper surface of the pile should be kept sufficiently below the upper end of the chute that the entering signatures fall for a substantial distance, for instance several inches, without appreciable contact with other signatures, and in so falling are readily arranged in approximate alignment with the signatures of the stack within the chute by contact with the chute walls.

A more perfect alignment of the signatures is accomplished by mechanically vibrating the chute during the operation. For this purpose, I have provided an electrically operated vibrator represented at 36, as more clearly shown in Figures 3 and 4 of the drawings. This vibrator is suspended on brackets 37 bolted to the rear side wall 10 of the chute. By thus vibrating the chute, the signatures can usually be brought into substantially perfect alignment without bending, or otherwise damaging, the edges of the individual signatures.

However, when operating the press at extremely high speeds, such that the signatures are delivered extremely rapidly to the chute, I have found it particularly advantageous to provide certain additional safeguards and auxiliary aligning guides, as hereinafter described.

In usual operation, the signatures will be delivered to the chute with their folded, thicker edge adjacent the rear end wall 10. In extremely high speed operation, I have found it advantageous to provide means for tilting the front edge of the signatures slightly upwardly and for urging the folded edge of the signature against

the rear side wall 10. For this purpose, I have provided at the opposite side of the entrance of the signature to the chute, an upwardly and outwardly tapering guide member 38 and a second member 39 positioned on the front side wall at the far end of the chute and having a bevelled forward edge.

Also, with advantage, the chute is provided near its exit with top guides 40 and 40' having their lower surfaces curved to conform generally to the curvature of the rear side wall 10 and spaced therefrom a distance equal to the width of the signatures to be stacked. Where desired, these additional guides for the upper surface of the stacked signatures may be provided by a downward extension of the front side wall 9. In either case, these curved guides, in conjunction with the vibrating of the chute, have been found effective in pushing downwardly into the stack any signatures which might extend slightly above the upper surface of the stack.

In the drawings, the curved guide 40 is shown as secured at its forward edge to the side plate 9 by means of bracket 41 and supported at its outer end by means of bolt 42 secured to end plate 8. The guide 40' is likewise supported at its rear end by front side plate 9 and at its outer end by means of bracket 44 secured to the rear bearing block 27.

As previously noted herein, the chute is, with advantage, tilted slightly upwardly at its entrance end so that its end walls 7 and 8 are inclined somewhat from the vertical plane, advantageously at an angle of about 6 to 12° from the vertical. The purpose of this is so that the end wall 7 will act more effectively as an aligning surface for the separately entering signatures. I have found, however, that where the signatures are shot against the end wall 7 with excessive momentum, there is sometimes a tendency for them to rebound. Also, where the delivery of the signatures to the chute is at relatively low speed, they may not, at times, have sufficient momentum to pass entirely into the chute and thus may accumulate just inside the chute entrance.

To avoid these conditions just noted, I have, with advantage, provided at the entrance of the chute, means for urging the signatures into the chute for their full length and for urging the rear end of the signatures downwardly into the chute and toward the back side wall 10 and end wall 7 which serve as aligning surfaces for the edge of the signatures.

For this purpose, as shown in Figs. 3, 4 and 5 of the drawings, I provide at the entrance of the chute a pair of conveyor belts 45, of the timing belt type previously described, mounted on idler sprockets 46 and driven sprockets 47. The inner face of these belts extends downwardly for a short distance along end wall 8 of the chute, extending inwardly from the wall only a sufficient distance to make contact with the signatures. The sprockets 46 are so positioned with respect to the conveyor belt 35 that the signatures entering the chute from conveyor 35 pass in contact with the upper surfaces of the belts 45, which are normally driven at a linear speed considerably higher than the velocity of the entering signatures, thus insuring that the signatures entering the box to their full width independent of their momentum. Also, in passing downwardly along the face of the chute these belts 45 urge the rear ends of the signatures downwardly into the chute.

The sprockets 47 are driven by shaft 48, supported by bearing block 49. The shaft 48 is, in turn, driven through sprockets 50 and 51 and timing belts 52 by means of variable speed motor represented at 53.

As further means for urging the signatures downwardly into the chute and against the rear side wall 10 thereof, I provide adjacent the front end wall 8 a rotatably mounted knurled disc 54, secured to shaft 55 and adapted to rotate so that its knurled surface moves downwardly within the chute while projecting only slightly inwardly of the inner face of the front side wall 9 so as to make

contact with the edges of the signatures. The knurled disc is mounted on shaft 55 and driven by variable speed motor 53 through sprocket 51 and shaft 56 and the sprocket 57 and timing belt 58 shown in dotted lines in Figure 5 of the drawings.

Should the aligned signatures pass too slowly from the chute, they might accumulate therein to a height which would not allow adequate free fall of the entering signatures to permit their ready alignment while out of contact with adjacent signatures. In order to avoid such condition, I provide automatic means for giving an alarm or for automatically increasing the speed of conveyor belts 24 whenever a predetermined height of the signatures in the chute is exceeded. For this purpose, I have, with advantage, equipped the chute with an electric eye 60 and a beam projector 61 so positioned with respect to the eye and to the chute as to direct and receive, respectively, a beam passing transversely through the chute just above the level of the predetermined maximum height to which the signatures are permitted to accumulate therein.

The electric eye 60 is supported to the rear of the chute by means of bracket 62 secured to the base frame of the machine and the beam projector 61 is supported by bracket 63 also secured to the base frame through journal block 64. Positioned on the front side wall 9 of the chute there is provided a lug 65 in the path of the beam and having an opening through the body thereof to permit passage of the beam and more accurately to control and restrict the path of the beam through the chute.

The elements 61 and 60 will, of course, be electrically connected, by means not shown in the drawing but readily known to the art, to a source of electrical energy and to an alarm or automatic speed control device, respectively. When the pile of signatures within the chute becomes so high that an entering signature fails to slip over the lug 65, the beam will be interrupted and the electric eye will automatically signal for a correction of the condition.

In order to assist the moving of the stacked and aligned signatures horizontally through the lower portion of the chute and to pack them more tightly on the receiving table, I provide on each side of the chute exit knurled cylinders 66 and 67 adapted to be rotated in contact with the respective edges of the stacked and aligned signatures. The knurled cylinder 66 is secured to shaft 68 supported by journal block 64 and is adapted to be driven through bevelled gears 69, shaft 70, sprocket 71, and drive chain 72 from any convenient source, not shown in the drawing, advantageously a variable speed motor.

Knurled cylinder 67 is secured to shaft 73 supported by journal block 27 and adapted to be driven by means of bevelled gears from the shaft 70. The shaft 70 may also serve to drive the driven sprockets 22 over which the conveyor belts 24 pass and shaft 73 may also be used to support and drive the rear drive sprocket 25 over which belt 28 passes.

A particularly advantageous aspect of the apparatus described is the curvature at the lower portion of the chute. This not only constitutes means for delivering the stacked signatures to the receiving table in a horizontal position but is also designed to prevent uneven and excessive build-up of the stack in the chute along the folded edges of the signature which might cause a portion of the stack to slide forward with respect to another portion.

It will be recognized that the folded edges of the signatures will ordinarily be thicker than their opposite edges. The difference in thickness will vary with the type of paper used in the printing operation and the number of folded sheets per signature. For optimum results, the radius of the curvature of the wall 10 and the radius of the curvature of the guides 40 and 40', or of the extension of side wall 9 when that is used, should be so correlated, relative to the increase in thickness of the

folded edges of the signature, as to deliver each signature to the receiving table in a substantially vertical position.

By thus correlating the radius of curvature, there is no excessive build-up of the stack at the folded edges of the signatures and those edges are kept closely and evenly against the curved side of wall 10 and thereby precisely aligned.

In the apparatus shown in the drawings, the radius of curvature of the outer curve has, with advantage, been made about 12 inches, and that of the inner curve approximately 6 1/4 inches. These curves may be about a common center so that the distance between the upper and lower guides remains constant while providing a correspondingly greater linear distance along the outer curve to accommodate the greater thickness of the signature at their folded edges, each of the curved surfaces bearing at all times upon the respective signatures, thus acting as positive aligning surfaces.

In some instances, it is desirable to bring curved surfaces gradually closer together so as to exert a wedging action against the edges of the signatures as they moved downwardly through the curved portion of the chute while being vibrated the minimum distances between the curved surfaces being just the height of the stacked signatures. This may be accomplished by describing the curvatures about different centers.

For most advantageous operation, the upper curved surface should be of such curvature as to coincide with the normal curvature of the upper portion of the stacked and uniformly packed signatures and should be spaced from the lower curved surfaces, at least toward the lower end of the chute, a distance just equal to the width of the signatures. These conditions will, of course, vary with signatures of different dimensions and thicknesses.

Though I have described with considerable particularity, certain embodiments of my invention which have been found particularly useful, it will be understood that the invention is not limited to the specific elements described, except as defined in the appended claims.

I claim:

1. A machine for stacking in accurate alignment folded signatures as they are delivered from the folder of a rotary, web-type printing press, comprising in combination a chute of rectangular transverse section of dimensions conforming generally to the length and breadth, respectively, of the folded signatures to be stacked, the upper end of the chute being substantially vertical and unobstructed and its lower end being curved outwardly at an angle of about 90° and terminating in a substantially horizontal exit, means for directing the folded, unstacked signatures along a substantially horizontal plane into the upper, open end of the chute against an end wall thereof, means for vibrating the chute, a table for receiving the stacked signatures from the chute exit having its upper surface lying in the plane of the lower surface of the chute exit and extending outwardly therefrom, the surface of the receiving table comprising a conveyor for receiving the stacked signatures and adapted to be moved along the table in a direction away from the chute exit and means for holding the stacked signatures in a vertical position as they are moved along the table.

2. The machine of claim 1 further characterized in that the chute is tilted endwise at an angle of 6° to 12° from the vertical.

3. The machine of claim 2 further characterized in that the receiving table is tilted sideways at an angle of 6° to 12° from the horizontal to coincide with the chute exit and that it is provided with a guide substantially perpendicular to the table surface extending along the lower side of the table, said guide comprising a plane surface adapted to be moved along the table in a direction away from the chute exit.

4. The machine of claim 3 further characterized in that the side guide of the receiving table comprises pulleys

rotatably mounted at each end of the table about an axis perpendicular to the table surface, an endless belt extending around the pulleys, one outer face of the belt forming the face of the guide, and means for driving at least one of the pulleys.

5. The machine of claim 1 further characterized in that the conveyor surface of the receiving table comprises a plurality of belts adapted to be moved along the length of the table and means for so moving the belts at a uniform variable speed.

6. The machine of claim 1 further characterized in that the substantially vertical portion of the chute is delineated by a rear side-wall, on the side opposite the chute exit, an opposite front side wall and two end walls and is provided at the entrance for the signatures with guide means adapted to tilt and to deflect the entering signatures against the rear side wall thereof and comprising an inclined outwardly tapering member positioned at the forward side of the path of the entering signatures and a second member positioned on the front side wall of the chute and having a bevelled forward edge.

7. The machine of claim 1 further characterized in that there is provided within the chute, adjacent the entrance of the signatures thereto, movable surfaces adapted to be moved downwardly in contact with the edges of the signatures therein for urging the rear ends of said signatures downwardly in the chute.

8. The machine of claim 1 further characterized in that the front and rear walls of the chute are fabricated of transparent material and the chute is provided with automatic means for determining when the height of the pile of signatures within the chute has exceeded a predetermined level.

9. The machine of claim 1 further characterized in that the receiving table is provided at its outer end with

15

20

25

30

35

a cradle comprising an arm adapted to extend longitudinally along the table and flush with the table surface, an end bracket extending substantially perpendicular to said arm, said cradle being hinged to the outer end of said table and adapted to be swung through an angle of 90° to bring said arm to a substantially vertical position.

10. The machine of claim 1 further characterized in that there is provided at each side of the chute exit a knurled cylinder rotatably mounted about axes perpendicular to the plane of the table surface, the knurled surfaces of said cylinders being spaced apart a distance substantially equal to the length of the signatures to be stacked and adapted to be rotated in contact with the edges of said signatures in a direction to urge the stacked signatures toward the receiving table.

11. The machine of claim 1 further characterized in that the radius of the curvature of the lower end of the chute is so correlated with the difference in thickness of the folded edge, and the opposite edge, of the signatures to be stacked as to provide a correspondingly greater linear distance along the outer side of the curve.
